(57) **CLAIM**

The ornamental design for a sculpture, as shown and described.

DESCRIPTION

FIG. 1 is a top front perspective view of a sculpture showing my new design;

FIG. 2 is a front elevation view thereof, the rear elevation view being a mirror image thereof;

FIG. 3 is a right elevation view thereof;

FIG. 4 is a left elevation view thereof;

FIG. 5 is a top elevation view thereof; and,

FIG. 6 is a bottom elevation view thereof.

The broken lines shown in the drawings depict environmental structure that forms no part of the claimed invention.
